US00D886167S

(12) **United States Design Patent** (10) **Patent No.:** **US D886,167 S**
(45) **Date of Patent:** **** Jun. 2, 2020**

(54) **3D PRINTER**

(71) Applicant: **Shanghai Furling Electronic Technology Co., Ltd.**, Shanghai (CN)

(72) Inventor: **Yunkai Wang**, Shanghai (CN)

(73) Assignee: **Shanghai Furling Electronic Technology Co., Ltd.**, Shanghai (CN)

(**) Term: **15 Years**

(21) Appl. No.: **29/642,096**

(22) Filed: **Mar. 27, 2018**

(30) **Foreign Application Priority Data**

Sep. 27, 2017 (CN) 2017 3 0464242

(57) **CLAIM**

The ornamental design of a 3D printer, as shown and described.

DESCRIPTION

FIG. 1 is a front perspective view of the 3D printer;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The details shown in broken lines are for illustrative purposes only and form no part of the claimed design.
